UNITED STATES PATENT OFFICE

2,013,227

CARTON

Dorian M. Wilson, Kalamazoo, Mich., assignor to
Sutherland Paper Company, Kalamazoo, Mich.

Application April 27, 1934, Serial No. 722,659

2 Claims. (Cl. 206—44)

The main objects of this invention are:

First, to provide an improved carton or container for baked goods and the like having windows therein so that the contents of the box may be 5 inspected without removing the same therefrom.

Second, to provide a carton or container of this character which is attractive in appearance and simple and economical in its parts, the arrangement being such that the box is not weakened by the windows.

Third, to provide a container having these characteristics which may be shipped in the flat and readily set up for use.

Objects relating to details and economies of my 15 invention will appear from the description to follow. The invention is defined and pointed out in the claims.

A structure which is a preferred embodiment of 20 my invention is illustrated in the accompanying drawing, in which:

Fig. 1 is a perspective view of a carton embodying the features of my invention, a cake being shown in the carton for purposes of illustration.

Fig. 2 is a section on line 2—2 of Fig. 1, the cake 25 being shown in broken lines.

Fig. 3 is a plan view of the blank ready for erection.

Referring to the drawing, in the illustrated embodiment of my invention, numeral 1 in general 30 indicates an integral blank of paper board, container board or the like which is cut and scored to provide a top 2 having side walls or panels 3 and 4 and end walls or panels 5, 5 extending therefrom. The end walls or panels are provided 35 with tuck-in bottom flaps 6. I provide the side wall 3 with locking end flaps 7, 7, the side wall 4 being provided with plain end flaps 8, 8.

The bottom 9 is connected to the side wall 4 and is provided with an inner side wall flap 10 40 having locking end flaps 11, 11 adapted to be interlocked with the corresponding end flaps 7, 7 of the adjacent side wall 3.

I provide the top 2 with four similar diamond-shaped windows 12 extending into the side walls 3 and 4 and end walls 5, 5 as shown. The windows are cut so as to provide triangular corner supports 13 and diagonal supports 14, 14 crossing at the center of the top. The corner supports and diagonal supports act to preserve the shape and 50 strength of the top of the carton.

I cement or glue a square sheet of transparent material 15 to the inner side of the blank 1 so as to provide panes for the windows 12. The sheet of transparent material is arranged with 55 its corners at the apexes of the windows in the side walls as shown. The contacting surfaces of the transparent sheet 15 and the blank 1 are firmly cemented or glued together so that the transparent sheet constitutes a substantial reinforcing for the top and side walls of the box.

With the parts arranged in this manner, the strength of the carton is increased rather than diminished by the provision of the windows.

The blank 1 is folded into erected position as 5 shown by Figs. 1 and 2, the inner side wall flap 10 being provided with a V-notch 16 so that the apex of the window in the corresponding side wall 3 is not covered by the flap. The cake 17 is placed in the carton by opening one of the end walls 5. The cake is protected from dust 10 and handling by the carton and may be readily inspected through the windows 12, the side wall window extensions permitting the inspection of the sides of the cake. The cake is readily removed from the carton by opening one of the 15 end walls 5.

I have illustrated and described my improvements in an embodiment which I have found very practical. I have not attempted to illustrate or describe other embodiments or adaptations as it 20 is believed this disclosure will enable those skilled in the art to embody or adapt my improvements as may be desired.

Having thus described my invention, what I 25 claim as new and desire to secure by Letters Patent is:

1. A carton comprising an integral blank having a top, side and end walls depending from said top, tuck-in bottom flaps on said end walls, end flaps on said side walls, a bottom connected 30 to one side wall, an inner side wall flap extending from said bottom and provided with end flaps interlocked with the corresponding end flaps of the adjacent side wall, the top having diamond-shaped windows extending into the side and end 35 walls and providing triangular corner supports and diagonal supports crossing at the center of the top, and a square sheet of transparent material cemented to the inner side of said blank and providing panes for said windows and reinforcing for said top and side walls, the sheet being arranged with its corners at the apexes of the windows in the side walls.

2. A carton comprising a blank having a top, side and end walls depending from said top, tuck- 45 in bottom flaps on said end walls, end flaps on said side walls, a bottom connected to one side wall, an inner side wall flap extending from said bottom and provided with end flaps interlocked with the corresponding end flaps of the adjacent 50 side wall, the top having diamond-shaped windows extending into the side and end walls and providing triangular corner supports and diagonal supports crossing at the center of the top, and a sheet of transparent material cemented to 55 the inner side of said blank and providing panes for said windows and reinforcing for said top and side walls.
